UNITED STATES PATENT OFFICE

ALPHONSE ARTHUR PICARD, OF NEW YORK, N. Y.

WHEEL-TIRE.

1,115,566.

Specification of Letters Patent.

Patented Nov. 3, 1914.

Application filed October 4, 1913. Serial No. 793,267.

To all whom it may concern:

Be it known that I, ALPHONSE ARTHUR PICARD, a subject of Great Britain, and a resident of the borough of Manhattan, city, county, and State of New York, have invented certain new and useful Improvements in Wheel-Tires, of which the following is a specification.

My improvements relate to a "floating rim" tire of the character designated in my Letters Patent No. 1,071,953, issued to me Sept. 2nd, 1913, and designed primarily to afford a simple but effective substitute for the inflated tire, overcoming the difficulties and inconveniences involved in the use of the latter, and attaining other practical advantages, such as strength combined with resilience and durability, comparative cheapness, &c.,—the distinctive feature of the present invention consisting in the interposition, between the central fixed base rim and the annular flange of the floating tire rim, of a series of elastic resilient cushions which reinforce and sustain the floating rim under strain while allowing it to adapt itself thereto under all conditions of use as hereinafter described and claimed specifically.

In the accompanying drawings, Figure 1, is a transverse section of my improved tire in which annular truss struts are used as in my Letters Patent hereinbefore referred to; Fig. 2, is a similar view in which said annular truss struts are omitted, and my elastic resilient cushions are relied upon entirely to sustain the floating rim; Fig. 3, is an end view of the cushion shown in Fig. 1, upon a larger scale; and Fig. 4, a side elevation thereof; Fig. 5, is a side view, and Fig. 6 an edge view of one of the cushions shown in Fig. 2, on a larger scale; Fig. 7, a section upon plane of line 7—7 Fig. 5; Fig. 8, a section upon plane of line 8—8, showing also the retaining bolt in cross section; Fig. 9, a sectional detail showing a modification; Fig. 10, is a diagrammatic view representing on a small scale the use of a plurality of my compensating cushions of the form shown in Fig. 9.

50 B represents the central base rim attached to the spokes S, of the wheel or otherwise rigidly connected with the hub thereof. This base rim B is formed with an annular groove or recess b.

55 A is the auxiliary "floating" annular rim upon the peripheral side of which is mount-

ed a solid tread t, of elastic resilient material, the external surface of which is preferably curved convexly as related to its cross section so as to afford a limited contact with the ground. The rear of the auxiliary rim A is formed with a central annular flange a, the inner portion of which fits in the annular groove b, in the base rim B, so as to be supported laterally by the sides thereof, 60 the groove b, being of sufficient depth to admit of the requisite degree of play between the parts.

In Fig. 1 elastic resilient annular truss struts s, s, are interposed between the flanges b', b', and the auxiliary rim A,—as in my Letters Patent hereinbefore recited; the edges of said struts s, s, being secured in place by the use of suitable mechanical expedients. Thus the outer edges of the truss 70 struts s, s, are secured to the annular flange a, by means of screw bolts c,—annular washer plates d, d, being interposed between these edges of the struts s, s, and the bolt heads and nuts. In similar manner the 75 inner edges of the truss struts s, s, may be secured to the outer edges of the base rim flanges b', b', by means of ring plates e, e, and screw bolts e', e', and nuts e², e²; and the flanges b', b', may be formed with annular 80 beads or shoulders b², b², to engage with corresponding grooves in the opposed surfaces of the struts s, s, for the purpose of preventing the lateral creeping of the said 85 struts.

When used in connection with the truss struts s, s, my series of compensating cushions k, k, are designed to supplement and control the action of the said struts s, s, reinforcing them against undue strain and limiting their extent of flexure, and this combination is desirable where the said truss struts are used on tires subjected to especial strain, as in the case of vehicles designed for heavy traction, such as automobiles and 95 wagons employed for purposes of commercial transportation, &c. For lighter vehicles however, and to economize in space and render the tire more simple and compact in structure the truss struts s, s, may be dispensed with and my compensating cushions k, k, relied upon entirely to afford the requisite degree of elasticity and resilience, as in Figs. 2 and 9.

In any case the essential feature of my 110 present invention consists in the use of a plurality of these compensating cushions

k, k, arranged equi-distant around the wheel, and, to all intents and purposes, interposed between the side walls *b^x, b^x*, of the annular groove *b*, in the base rim *B*, and the central annular flange *a*, of the auxiliary rim *A*, in such manner as to admit of the requisite degree of motion between said parts while acting as elastic resilient media to absorb and compensate for the shock and strain of traction. Obviously the form and arrangement of my intermedial compensating cushions *k, k*, may be varied without departing from the spirit and intent of my invention. Thus in Fig. 1, a plain cylindrical cushion *k*, of elastic resilient material, shown in detail in Figs. 3 and 4, is simply seated in recesses *b³, b³*, in the side walls *b^x, b^x*, of the base rim *B*, and the recess *a'*, in the annular flange *a*, of the auxiliary rim *A*, said recesses coinciding with each other when the tire is not subjected to strain which is the position assumed for convenience of illustration in the drawings. In this arrangement shown in Fig. 1, side caps *f, f*, may be used to prevent the displacement of the intermedial compensating cushions *k, k*; and the edges of the recesses *b³, b³, a'*, may be rounded off to prevent shearing action and afford space for the compression of the cushions.

In Fig. 2, separate compensating cushions *k, k*, are situated in each of the recesses *b³, b³*, of the base rim *B*, mounted axially upon a bolt *g*, seated in the recess *a'*, in the annular flange *a*, of the auxiliary rim *A*—the head of the bolt and the retaining nut *g^x*, being flanged, or washers being used to cover the recesses *b³, b³*.

An alternative construction is shown in Fig. 9, in which an intermedial compensating cushion *k*, is positioned in each recess *a'*, (enlarged for the purpose) in the annular flange *a*, of the auxiliary rim *A*, and the bolt *g*, is seated in the (contracted) recesses *b³, b³*.

In either case the size of the intermedial compensating cushions *k*, is proportionate

to the extent of play and elastic resilient resistance called for by the requirements of use for which the tire may be designed.

50

When used as illustrated in Figs. 2 and 9, the cushions *k*, may be in the form of disks having side concavities *k'*, to facilitate the compression of the rubber composition or other elastic resilient material of which the cushions may be formed.

The number of intermedial compensating cushions *k*, used, their size, and their distribution around the base rim *B*, will depend upon the character and requirements 60 of the vehicle to be fitted with this form of tire.

In order to prevent undue frictional heating by reason of the turning of the cushions *k, k*, upon the retaining bolts or within the recesses I form the contacting parts with interlocking ribs and grooves which prevent rotation,—as the ribs *r*, on the cushions fitting in corresponding grooves in the bolts *g, g'*, and in the side walls of the recesses 70 *b³, b³, a'*, or alternatively vice versa, as may be desired or found most expedient.

What I claim as my invention and desire to secure by Letters Patent is,

In a tire of the character stated, a base 75 rim formed with an annular groove having recessed side walls, an auxiliary floating annular rim formed with a central flange freely slideable in said groove, said flange being recessed coincident with the recesses 80 in the side walls of the base rim groove, elastic resilient cushions positioned intermediately in the recesses of said base rim and annular rim, and means bearing against the outer faces of the base rim opposite said 85 recesses and holding said cushions in place, said resilient cushions and recesses having interlocking ribs and grooves to prevent rotation of the cushions.

ALPHONSE ARTHUR PICARD.
